GUIDE MEANS

Raymond Liona, Brooklyn, N. Y.

Application August 16, 1946, Serial No. 690,902

3. Claims. (Cl. 191—415)

1

This invention relates generally to printing machine accessories and has particular reference to guides for platens thereof.

One of the objects of the invention is the provision of guide means of this type which are of a general utility; that is to say, guides which are of advantage, because of their utility and novelty, for automatic presses and also for those using hand means, and guides which call for no space or occupied area on the margin of the 10 platen workpiece.

This invention, moreover, has for objects thereof the provision of guides which are inexpensive to manufacture, simple, consistent with efficiency, and effective for holding the edge of a piece of paper on the platen of the machine, in such manner that when the printing is done it will register in the proper position on the paper; also to construct the device in such manner that it may be used in extending beyond the edge of the platen, so as to both support and guide the paper; to make the device in such way that it will not injure the platen sheet or tear the same when being used; and it consists, essentially, of a holder comprising a horizontal portion and a downwardly-extending flange adapted to be gripped between the platen and the bail 11, for example, and a strip slidably held on said horizontal portion and having guiding means at one end, the various parts of the device being constructed and arranged in detail, as hereinafter more particularly described.

With the above indicated objects and advantages in view as well as others which will herein-after appear, the invention resides in certain novel constructions and arrangements of parts, the essential features of which are herein fully described, and illustrated in the accompanying drawing, in which:

Fig. 1 is a view in perspective of a printing machine platen, on which are shown in plural numbers embodiments of the instant invention.

Fig. 2 is an enlarged section on the line 2—2 of Fig. 1.

Figs. 3 and 4 are respectively top and under-side views of a feed guide shown in Fig. 1.

Fig. 5 is a plan view of another guide shown in said Fig. 1.

Fig. 6 is a section on the line 6—6 of Fig. 5.

Fig. 7 is a central sectional view of another embodiment of the invention; and

Fig. 8 is an end view of Fig. 7.

Fig. 9 is a plan view of a modified form of the invention.

As shown in said drawing, the disclosure in-

cludes a platen 10 having edge clamping means 11, 11, and a sheet, as 12 of paper, disposed in working position thereon.

A guide means for the workpiece 12 includes a unit having a sheet metal leaf member 13 with a slot 14 therein running from the split end 15 thereof.

Slidably embracing the leaf 13 is a member 16, the latter having two side flanges 17, 17, embracing said leaf, and in the body portion 16 thereof is an aperture, which receives a releasable holding element in the form of a bolt 18 having a nut 19.

Depending from the member 16 is a flange 20 which in the working position finds a seat inside of the clamp 14, and on the opposite end of the device, on the member 13, is a suitably limited depending guide flange 21. At this point it is noted that in Fig. 1 is shown a pair of the guide units, and the members of this pair are alike, so that a description of one is applicable to the other.

At the juncture of the flange 21 with its body member 13 is a pair of apertures 22, 22 between which may also be an aperture 23, for a third pin if three pins are used instead of two. Passing through the apertures 22 are the terminals 24, 25 of a wire extension having a looped medial part 26 slidably embracing the member 13 thereat. 30 At the adjacent edge of the sheet 12 enters against and engages the flanges 21, 21, and the terminals 24, 25 are so arranged (see Fig. 2) as to be advantageously disposed above and adjacent the margin of said sheet.

Substantially similar to the guides having the flanges 21 engaging the edge 30 of the workpiece 12 is a guide means having a fixed wire extension 125 overlying and thereby engaging the sheet 12 at its margin 31, this modified guide means 40 including a projecting member 113 similar to member 13 and having a slot 114. Embracingly disposed on the member 113 is a transversely disposed member 116 having side flanges 117, and adjoining the member 116 with its flanges, are keeper elements 32, 32, while screw or bolt 118 retains the member 116 slidably in position. The member 113 passes through slots in the member 116 at the folds of the flanges 117. An anchorage flange 121 forms a portion of a leaf member 35, also embraced by the flanges 117 and this member 35 may have thereon channel shaped keeper elements 36, 36 with flanges 136, 136 engaging the edges of member 35 to guide the same.

As shown in Figs. 7, 8, a flat leaf member 213, shown in side elevation and end elevation, has

thereon a guide flange 221 at one end and a hinged anchorage flange 220 at the other end, as well also as a member 216 and holding means 18.

In this latter case a wire extension means 226 may have its terminals as 225, upwardly turned, as shown. Between the member 213 and its hinged anchorage 220 is a torsion spring 38 mounted on hinge 217, which tends to urge the flange 221 downwardly against the platen 10, and this guide means may therefore be swung upwardly to be automatically returned by said spring.

In the form shown in Fig. 9, a sliding member 316 has an upwardly extending flange 321 provided with apertures to receive terminals 324, 325 of a wire extension 326, slidably mounted on the member 316 and held in adjustment by a screw 18.

Variations may be resorted to within the scope of the invention and parts of the improvements may be used without others.

I claim:

1. Guide means for a printing press platen having an edge clamp or bail, the guide means comprising a sheet metal flat leaf member having a slot portion extending inwardly thereon from one end thereof, a second transverse sheet metal member overlying a portion of the flat leaf member and having a depending flange adapted to be engaged between the edge of the platen and the clamp and having side flanges engaging the side edges of the flat leaf member and being extensibly slidably thereon, there being a bore in the second transverse member registering with the slotted portion in the first member, means retaining both members selectively through said bore, an end of the leaf member, opposite from that in which the slot extends being imperforate and having a rigid depending guide flange, there being also a pair of apertures spaced apart at the top of said depending flange, and wire means engaging said imperforate end slidably and terminating in a pair of projecting ends extending outwardly through said pair of apertures.

2. Guide means for a printing press platen having an edge clamp the guide means including a flat sheet metal leaf member having a depending rigid guide flange for a workpiece on said platen, there being a pair of apertures in said flange, a generally U-shaped wire element having the intermediate portion thereof slidably engaging a portion upon said sheet metal leaf member and having the limbs thereon projecting through said pair of apertures and terminating beyond said leaf member, and an anchoring flange disposed at the other end of said leaf member for engagement between the clamp and the edge of the platen.

3. Guide means for a printing press having a platen provided with a clamp, the guide means including a sheet metal leaf member having a guide flange upon one end with a perforation therein and a retaining flange at the other end adapted to be engaged between the clamp and the edge of said platen, and a narrow elongated member engaging with a portion upon said leaf member and having one end projecting outwardly through said perforation at a level above that of a work sheet lying upon said platen against the guide flange.
